(57) **CLAIM**

The ornamental design for a coffee grinder with a short storage length and a long working length as shown and described.

DESCRIPTION

FIG. 1 is a front, top and right side perspective view of a coffee grinder with short storage length showing my new design in accordance with a first embodiment;

FIG. 2 is a rear, bottom and right side perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1;

FIG. 8 is a bottom plan view of FIG. 1;

FIG. 9 is an enlarged view of a section 9 of FIG. 1;

FIG. 10 is the coffee grinder with a short storage length of FIG. 1 with a powder container and a cover at both ends of the coffee grinder disassembled;

FIG. 11 is a front, bottom and right side perspective view of the coffee grinder at a long working length in accordance with a second embodiment, where positions of the powder container and the cover are interchanged at both ends of the coffee grinder; and,

FIG. 12 is the coffee grinder at a long working length of FIG. 11 with the powder container and the cover at both ends of the coffee grinder disassembled.

The broken lines at least in FIGS. 1, 3, 5-7 and 10-12 depict environmental structure. All broken lines form no part of the claimed design.

1 Claim, 12 Drawing Sheets
